(57) **CLAIM**

The ornamental design for an electrode plate for a semiconductor manufacturing apparatus, as shown and described.

DESCRIPTION

FIG. 1 is a perspective view of an electrode plate for a semiconductor manufacturing apparatus.

FIG. 2 is a front elevational view of the electrode plate.

FIG. 3 is a rear elevational view of the electrode plate.

FIG. 4 is a left side elevational view of the electrode plate.

FIG. 5 is a right side elevational view of the electrode plate.

FIG. 6 is a top plan view of the electrode plate.

FIG. 7 is a bottom plan view of the electrode plate; and,

FIG. 8 is a cross-sectional view taken along line 8-8 of FIG. 6.
